UNITED STATES PATENT OFFICE.

EMERY FISHER, OF CORDAVILLE, MASSACHUSETTS.

IMPALEMENT-TRAP FOR HOUSE-BREAKERS.

SPECIFICATION forming part of Letters Patent No. 355,070, dated December 28, 1886.

Application filed June 16, 1886. Serial No. 205,349. (No model.)

To all whom it may concern:

Be it known that I, EMERY FISHER, a citizen of the United States, residing at Cordaville, in the county of Worcester and State of Massachusetts, have invented certain new and useful Improvements in House-Protectors; and I do hereby declare the following to be a full, clear, and exact description of the invention, such as will enable others skilled in the art to which it appertains to make and use the same.

My invention has for its object to provide a house-protector which will guard the premises, whether they be bank, store, or dwelling, against the entrance of a house-breaker or burglar, and at the same time will entrap and secure the burglar, so that he may be brought to summary justice. The protector can be applied to structures already erected as well as to buildings under course of erection, and, besides serving the useful purpose indicated, may serve to ornament the window to which it is attached.

To the accomplishment of the foregoing ends the invention consists in the construction, and in the combination of parts, hereinafter particularly described, and then sought to be specifically defined by the claims.

In the drawings forming part hereof, Figure 1 is a front elevation of a window, looking from the inside, having my invention applied thereto, parts being in section and the protector set for action. Fig. 2 is a transverse vertical section through the same.

The letter A designates a window-frame provided with the upper and lower sashes B and C, all of which parts are generally of the ordinary and well-known construction.

The sides of the frame in front of the sash are formed in any suitable way, with ways D extending from the top to the bottom of the frame, and in these ways fit the opposite side edges of a slide, E. This slide is weighted in any suitable manner, preferably by constructing it of boiler-iron or other suitable metal, and is formed at its side edges with ratchet-teeth a, and along its lower or bottom edge is provided with downwardly-projecting pins or teeth F, which are preferably concealed by a hanging fringe, G. The lower part of the slide from which the teeth project is preferably cut away or recessed, as seen at one side

in Fig. 1, where the fringe is cut away, as at b, to show the construction, so that the teeth will terminate on a line with the lower edge of the slide, as seen in that figure. The slide is raised by a chain or rope, H, connected to the upper end of the slide and passed over pulleys I and J, and then down one side to the lower part of the frame, where it is connected with a suitable catch—for instance, with a finger or pin, K. It is preferably connected with this pin nearer to one end than to the other, so that the pin can be more easily disengaged from a notch, c, formed in the side of the frame, as illustrated in Fig. 1. The short end of this pin engages with a notch, d, formed in a spring-actuated bar, L, connected with the window-sill M. The sill is preferably recessed, so that the bar will lie in it, the bar being hinged at one end in any suitable manner—for instance, by a pivot, e—to the sill. The bar is made elastic or yielding in any suitable way—for instance, by a spring, f, interposed between it and the sill.

When the parts are in the position shown in Fig. 1, the protector is set so that when pressure is applied to the spring-bar it is depressed, thus releasing the catch K, when the weight of the slide will cause it to fall by gravity until checked by striking an object between it and the sill. It will thus be seen that when a burglar raises the sash and rests his hand or body on the sill or bar in entering through the window he at once releases the catch and is caught between the slide and window-sill.

The slide is prevented from being raised by the man between it and the sill by means of spring-catches N, secured to the window-frame in recesses formed therein, and made to project inwardly so as to engage with the ratchet-teeth on the sides of the slide. These spring-catches may be formed with ratchet-teeth g to engage the ratchet-teeth of the slide. The catches are also formed with fingers h, which project through openings i, made in the frame, so that a bar (indicated by dotted lines in Fig. 1 and designated by the letter O) may be extended across the sash and pressed against the fingers to hold the same out of engagement with the ratchet-teeth of the slide, and thus permit the slide to be raised. When the pro-

tector is set for action, the cross-bar is removed so that when the slide falls its teeth will engage with the spring-catches.

If the burglar happens to be in a somewhat raised posture when the slide strikes him and stoops or bends to get from beneath it, the slide will, by its weight, quickly follow the downward movement of the body and so hold the burglar. It cannot be raised by him, because every time it makes a movement downward the spring-catches engage with another tooth in the sides of the slide and so prevent it from being raised. The spring-catches are too high up to be reached from the outside, and consequently the protector can only be released from the inside, so that the burglar will be held until captured and released from the inside of the building.

Both sides of the slide will be painted and decorated, so as to be ornamental and look like a blind or curtain.

During the day, and when the protector is not to be operated, the slide is held up securely and safely by a hook, P, hinged thereto and engaging with an eye, Q, in the upper part of the window-frame.

I have described suitable means for carrying out my invention, but do not restrict my-

self to details of construction of the several parts, as it is obvious that they may be altered without departing from the spirit of my invention.

Having described my invention and set forth its merits, what I claim is—

1. The combination, with a window, of the vertically-moving slide formed with ratchet-teeth, the spring-catches connected with the window-frame to engage with said teeth, the rope connected with the slide and connected with the catch at its lower end, and the spring-actuated bar at the sill of the window, engaging with the catch connected to said rope, substantially as and for the purpose described. 35

2. The combination, with the window, of the vertically-moving slide, a catch connected with the slide and serving to hold it in an elevated position, and a bar located at the base of the window and operating on said catch to release it and permit the slide to fall, substantially as described. 45

In testimony whereof I affix my signature in presence of two witnesses.

EMERY FISHER. [L. S.]
